DESIGN FOR A CONFECTIONERY PRODUCT

Edward L. Schoettle, Cincinnati, Ohio, assignor to The John Mueller Licorice Company, Cincinnati, Ohio, a corporation of Ohio

Application April 10, 1940, Serial No. 91,582

Term of patent 7 years

To all whom it may concern:

Be it known that I, Edward L. Schoettle, a citizen of the United States, residing at Cincinnati, in the county of Hamilton and State of Ohio, have invented a new, original, and ornamental Design for a Confectionery Product, of which the following is a specification, reference being had to the accompanying drawing, forming part thereof.

I claim:

The ornamental design for a confectionery product, as shown.

EDWARD L. SCHOETTLE.
